UNITED STATES PATENT OFFICE.

WESLIE M. ROADES, OF OKMULGEE, OKLAHOMA, ASSIGNOR TO UNITED IRON WORKS COMPANY, OF OKMULGEE, OKLAHOMA.

OIL-SAVER AND SAND-LINE CAP.

1,193,187.

Specification of Letters Patent.

Patented Aug. 1, 1916.

Application filed April 10, 1914, Serial No. 831,039. Renewed June 5, 1916. Serial No. 101,871.

To all whom it may concern:

Be it known that I, WESLIE M. ROADES, a citizen of the United States, residing at Okmulgee, in the county of Okmulgee and State of Oklahoma, have invented a new and useful Oil-Saver and Sand-Line Cap, of which the following is a specification.

By way of explanation it may be stated that in the operation of drilling oil wells, a closure or oil saver is attached to the casing head, around the cable, so soon as oil-bearing sand is struck, to the end that the oil may not flow out of the well. When the drilling operation is continued, ultimately, it becomes necessary to bail the well, and then the oil saver or closure is detached from the casing head but is left assembled with the drilling cable, the cable being hauled out of the well and a bailer being inserted. The bailer carries a sand line cap which is assembled with the casing of the well during the bailing process.

One object of the present invention is to provide a structure which may be adapted readily either to an oil saver or a sand line cap, to the end that either of these elements, and particularly the oil saver, may be mounted in place quickly upon the well casing, a delay of minutes not infrequently resulting in a considerable waste of oil and much damage to surrounding land and crops.

Specifically, the invention consists in dividing the saver, so that it may be placed readily around the cable and in dividing the bushing which is carried by the saver, so that the bushing may be placed on the cable and then be threaded into the saver.

Another object of the invention is to provide a novel form of latch mechanism, whereby the constituent elements of the device may be connected, the latch mechanism comprising no parts which are loose or detachable and likely to fall into the well, thereby prolonging greatly the application of the structure.

With the above and other objects in view which will appear as the description proceeds, the invention resides in the combination and arrangement of parts and in the details of construction hereinafter described and claimed, it being understood that changes in the precise embodiment of the invention herein disclosed can be made

within the scope of what is claimed without departing from the spirit of the invention.

In the accompanying drawings: Figure 1 is a side elevation of an oil saver constructed in accordance with the present invention; Fig. 2 is a top plan of the structure shown in Fig. 1; Fig. 3 is a side elevation, the view point being 90° remote from the view point in Fig. 1; Fig. 4 is a vertical section, wherein sundry parts appear in elevation; Fig. 5 is a side elevation of a sand line cap constructed in accordance with the present invention; Fig. 6 is a top plan of the structure shown in Fig. 5; Fig. 7 is a side elevation of the cap shown in Fig. 5, viewed from a different stand point; Fig. 8 is a longitudinal section of the structure shown in Figs. 5, 6 and 7.

Referring to Figs. 1, 2, 3 and 4, wherein the invention has been shown in the form of an oil saver, the invention comprises, generally considered, a body 1. The body 1 comprises the base plates 2 and 3. The base 2 is provided with an upstanding, semi-tubular neck 5 co-operating with a similar neck 6 on the base 3, these parts uniting to form a socket which is denoted generally by the numeral 7. The socket 7 is internally threaded as indicated at 8, and adjacent the lower end of the socket, the bore thereof is diminished in diameter to form a transverse shoulder 9. The neck 5 is provided with opposed pairs of lugs 10 and there are similar lugs 11 on the neck 6. Pivot elements 12 connect the lugs 10 of the respective pairs and upon the pivot elements 12 are mounted swinging latches. The latches preferably take the form of bolts 15 having eyes 14 located between the lugs 10, the pivot elements 12 passing through the eyes. Washers 16 may be mounted on the free ends of the bolts 15 and nuts 17 are applied to the free ends of the bolts. Cotter pins 18 or the like pass through the free ends of the bolts 15 and serve to prevent the nuts 17 from being detached accidentally.

The invention further includes a longitudinally split bushing, threaded into the socket 7 and comprising laterally separable parts 19, each part 19 being provided with a transverse head, the heads uniting to form a handle 20, the handle forming heads being doweled together as indicated at 21, if de-

sired. The bore of the separable bushing is indicated at 22 and a packing 23 is interposed between the inner end of the bushing and the shoulder 9. A pair of foot plates 24 may be secured to the bases 2 and 3 by means of attaching elements 25. When the plates 24 are omitted the plates 2 and 3 are received inside the casing head and the device is held in place by set screws (not shown) which come in contact with the beveled edges 4. The foot plates 24 are for the purpose of enlarging the base to fit down in larger sized casing heads thereby enabling one saver to take the place of two, the function of the beveled edges 26 of the plates 24 now being clear. The bolts or latches 15 are swung around until the same pass between the lugs 11 and then the nuts 17 are tightened up. It is to be observed that the nuts 17 need be loosened but slightly, and therefore the latching operation may be carried out with speed. Further, the nuts 17 cannot be detached from the bolts 15, owing to the presence of the cotter pins 18. As has been indicated hereinbefore, this latching up operation must be carried out rapidly and there must be no chance for any portion of the latching mechanism to be lost or deranged. The utility of the simple but effective structure above described will therefore be manifest. The parts 19 of the separable bushing are then placed around the cable, the handle forming parts 19 coming into cooperation with each other whereupon the bushing is threaded down into the socket 7 as shown in Fig. 4, the packing 23 being put under compression.

Many of the essential and important features hereinbefore described in connection with the oil saver may be resorted to in the formation of a sand cap such as that shown in Figs. 5, 6, 7 and 8. Referring to these figures, the body of the cap is indicated at 27 and comprises base portions 28 and 29, the necks being indicated at 31 and 32, the neck 31 having lugs 33 and the neck 32 having lugs 34. A pivot element 35 connects the lugs 33 of each pair and upon each pivot element is mounted to swing a bolt 36 provided with a washer 37 and a nut 38, the nut 38 being adapted to coöperate with the lugs 34. The cotter pin which limits the move-

ment of the nut 38 is shown at 39. The bore of the socket formed by the necks 31 and 32 is indicated at 40. Foot plates are shown at 41, and the securing elements 42 are employed for holding the foot plates in place. The operation of the sand line cap shown in Figs. 5, 6, 7 and 8 need not be gone into in detail in view of what has been said hereinbefore concerning the oil saver shown in Figs. 1, 2, 3 and 4. The function of the sand line cap is similar to the function of the oil saver, the sand line cap, however, being assembled with the bailer.

Having thus described the invention, what is claimed is:—

1. A device of the class described, comprising a base and an upstanding socket, the base and the socket being divided to form laterally separable parts; a latch permanently pivoted to one of said parts and mounted to swing transversely of the socket into and out of engagement with the other of said parts; a two part foot plate of greater diameter than the base; and means for removably securing the parts of the foot plate to the under faces of the respective parts of the base, the latch constituting means for holding the parts of the base and the parts of the foot plate, respectively, in transverse alinement.

2. A device of the class described, comprising a base, a socket upstanding from the base, and a foot plate applied to the under surface of the base, the foot plate being of greater diameter than the base, and the foot plate and the base being of substantially the same configuration to permit the base and the foot plate to conform to well casings of different sizes; the socket, the base and the foot plate being divided to form laterally separable parts; means for detachably securing the parts of the foot plate to the respective parts of the base; and means for holding all of said parts together against lateral displacement.

In testimony that I claim the foregoing as my own, I have hereto affixed my signature in the presence of two witnesses.

WESLIE M. ROADES.
